UNITED STATES PATENT OFFICE

GEORGE F. HARTER, OF SPRINGFIELD, MASSACHUSETTS, ASSIGNOR TO THE STANDARD ELECTRIC TIME COMPANY, OF SPRINGFIELD, MASSACHUSETTS, A CORPORATION OF CONNECTICUT

EMERGENCY DISPATCH SYSTEM

Application filed January 28, 1928. Serial No. 250,159.

This invention relates to electrical systems for closing a plurality of circuits in sequence, particularly dispatching systems for signalling the arrival or departure of trains, motor 5 busses or the like, and more particularly to emergency means for closing the circuits out of the normal sequence for any desired purpose as for example to signal the departure of trains or busses which are off schedule.

10 In applying the invention to dispatching systems the aforesaid circuits may be connected respectively to time and route signals of any desired character. For example, the route signals may comprise lights for illuminating the route boards respectively for an interval of five minutes before the time of departure and the time signals may comprise a chime to be rung five minutes before the time of departure, a gong to be rung one minute 15 before the time of departure and a warning light to constitute the "last call". The time signals may be common to the route signals so that one set of time signals will serve in connection with each route signal. These 20 signals are preferably controlled automatically by time and route means including synchronized controllers such as perforated-tape or pin-drum contact-closers controlled by a master-clock. So long as the trains or busses 25 maintain their regular schedule such a system is highly satisfactory but otherwise it is inadequate.

According to the present invention emergency apparatus is provided to produce the 30 desired sequence of signals for any train or bus which is off schedule, this apparatus preferably being correlated with a dispatching system of the aforesaid type to operate the usual signals in the usual sequence. In the 35 best mode of applying the invention of which I am aware, means are provided to shift the control of the signals relating to any particular departure to the emergency apparatus at any desired time, for example when it 40 is first learned that the departure must be delayed, the functioning of the emergency means then being initiated at a predetermined time before the delayed departure as by actuating a manual switch or other controller. 45 This shift of control to the emergency ap-

paratus may be effected for any particular route simply by the reversal of a two-way switch associated with the corresponding route board light, one contact of the switch being connected to the normal control mechanism and the other contact with the emergency apparatus. 55

The emergency apparatus preferably comprises a controller of the aforesaid perforated-tape or pin-drum type for closing the 60 circuits in the desired sequence. However, instead of using a twenty-four hour or other long-interval controller as in the normal-schedule apparatus the emergency controller need have only a single set of circuit-closing 65 perforations or pins which function for each cycle of emergency signals in connection with any one of the plurality of route boards. The emergency apparatus also comprises means for rendering it functionally ineffective at the 70 end of each cycle of signals, preferably by automatically stopping its controller in a rest position in which a control circuit is closed.

For the purpose of illustration one concrete embodiment of the invention is shown 75 in the accompanying drawing in which:

Fig. 1 is a diagrammatic representation of the entire system; and

Fig. 2 is a diagram of certain of the circuits of the emergency apparatus in a condition 80 other than shown in Fig. 1.

In the particular embodiment of the invention chosen for the purpose of illustration R and R' indicate route boards; 1 and 2 are 85 lights for illuminating the boards respectively; C, G and L the chime, gong and last-call light to be operated at predetermined times before the departure over any particular route, as for example five minutes, one minute and immediately before departure; 90 3, 4, 5, 6 and 7 are relays for closing the circuits of the respective signals; 8, 9 and 10 are so-called duration-contact relays for controlling the relays 5, 6 and 7 respectively; 11 is 95 a master-clock for closing circuit at predetermined intervals, for example once per minute; 12 to 16 inclusive are perforated tapes for controlling the circuits of the respective signals; 17 to 21 inclusive represent spring-contact fingers arranged to contact with a bar 100

22 through the perforations in the tapes respectively; and E is the emergency apparatus.

Each of the duration-contact relays 8, 9 and 10 comprises a notched wheel having alternate recesses 23 and protuberances 24 on its periphery, a circuit closer 25 carrying a lug 26 which rides on the periphery of the notched wheel and an electromagnet 27 for advancing the notched wheel one step each time it is energized, one step of the notched wheel constituting the distance between a recess 23 and a protuberance 24 so that successive energizations of the electromagnet 27 alternately opens and closes the switch 25, the switch remaining open or closed until the next energization of the electromagnet. Inasmuch as this is a common type of make and break relay further disclosure will be unnecessary herein.

Tape controllers of the type indicated at 12 to 21 are also well-known and therefore need not be shown in detail for the purpose of illustrating this invention, it being understood that the tapes are driven in synchronism by any suitable means under the control of a master-clock, that instead of using a separate tape for each series of perforations the respective series of perforations may be combined in any desired combinations on one or more tapes of multi-width. The tapes may have any desired length to cover any period of time, as for example a twenty-four hour period. Whenever one of the perforations 28 to 36, inclusive, is moved under one of the contact fingers 17 to 21, inclusive, circuit is closed through the finger and the contact bar 22 until the perforation is moved past the contact finger. The tapes are preferably advanced intermittently at short intervals of time and the perforations are preferably located on the tapes to register with the contact finger during the brief period when the tapes are at rest.

Inasmuch as the operation of that portion of the system above described is self-evident only a brief outline will be set forth as follows. As shown in Fig. 1 the signals relating to route R are next in order. When the tapes advance until the perforations 28 and 32 are in registry with the contact fingers 17 and 20, lamp 1 is lighted to illuminate the board R and chime C rings. The circuit for chime C is closed by the relay 3 which is energized through the circuit from ground to bar 22, contacting finger 17, relay 3 and master-clock switch 11 back to ground. The master-clock switch is synchronized with the tape so that it closes circuit during a fraction of each rest period of the tape. Consequently the relays 3, 4, 8, 9 and 10, which are controlled by the master-clock switch 11, do not remain energized during the entire period of rest of the tapes but only during a fraction of these periods. The circuit through lamp 1 is closed

by the energization of relay 6 whose circuit is closed by relay 9 which is energized over the circuit from ground to bar 22, finger 20, master-clock switch 11 to ground. While the relay 3 for chime C closes circuit only momentarily, the relay 9 maintains the circuit for light 1 closed until the relay 9 receives another impulse of current. Inasmuch as the perforations 28 and 32 move out of registry with the contact fingers before the master-clock switch 11 again closes contact the relay 9 does not receive another impulse of current until another perforation moves under spring finger 20. As the tapes advance the perforation 29 in tape 13 comes under the finger 18 after a predetermined series of time, whereupon the gong G rings for a brief interval, the gong G being controlled in the same manner as already described in connection with chime C. Shortly after the ringing of gong G perforation 30 comes under finger 19 thereby lighting the last-call light L in the same manner as already described in connection with the light 1. Shortly thereafter the perforations 31 and 33 move under the fingers 19 and 20, thereby extinguishing the lights L and 1 by advancing the relays 8 and 9 one step to a position where the lugs 26 register with the recesses 23 in the two notched wheels of the relays 8 and 9, respectively. This completes one cycle of signals, the train or bus over route R departing at the time the lights L and 1 are extinguished.

To repeat this cycle of signals for other routes only one additional tape per additional route is required. Thus, in Fig. 1 the additional tape 16 is added for route R', it being understood that as many additional routes as desired may be operated by this apparatus as indicated by the broken lines 37 and 38, the signal tapes 12, 13 and 14 serving for each route. For example, the perforation 36 on tape 12 moves under finger 17 at the same time that perforation 34 on tape 16 moves under finger 21, thus initiating a second cycle of signals, the tapes 12, 13 and 14 having recurrent sets of perforations bearing the same relation to perforations 34 and 35 on tape 16 and other tapes as the perforations 28, 29, 30 and 31 bear to the perforations 32 and 33 on tape 15.

The emergency apparatus E comprises a controller which may have a plurality of tapes as above described but for the purpose of illustration a single multi-width tape 39 is shown. This tape has four series of perforations in alignment with the contact fingers 40 to 43, respectively, perforations 44 and 45 aligning with fingers 40 and 41, respectively, perforations 46 and 47 aligning with finger 42 and perforation 48 aligning with finger 43. The circuits through fingers 40 and 41 are in parallel with the circuits through fingers 17 and 18 and function in the same way when the emergency apparatus is

in operation. The circuit through finger 42 controls any one of the route lights 1, 2, etc., when the corresponding switch 50, 51, etc., is moved to the dotted-line position. The fourth finger 43 controls the starting and stopping of the emergency controller as will now be described.

While the emergency controller may be advanced in any suitable way the illustration shows a ratchet drive 52 actuated by an electromagnetic motor 53 energized at recurrent intervals by a master-clock 54 which may be the same master-clock as controls the movement of the tapes 12 to 16, inclusive. The emergency apparatus also includes a two-way electromagnetic switch 55 operated step by step by an electromagnet 56 in the same way as relays 8, 9 and 10, a two-way manual switch 57 and a relay switch 58 operated by an electromagnet 59. For convenience the contacts of the two-way switches are referred to as the on and off contacts, the on contacts being designated N and the off contacts F.

The operation of the emergency apparatus is as follows. When the dispatcher learns for example that the train or bus over route R is delayed, the switch 50 is thrown from the solid-line to the dotted-line position, thereby preventing the tape 15 from lighting lamp 1 at the regular time. Then at a predetermined time before the delayed starting over route R the manual switch 57 is moved from contact F to contact N, thereby energizing electromagnet 56 through the contact N of switch 57 and the contact F of switch 55. This advances the notched wheel 60 one step to move the switch 55 from contact F to contact N, thereby breaking the circuit through electromagnet 56 and establishing circuit through the motor 53. When the motor 53 receives the first impulse from master-clock 54 the tape 39 is advanced to the next position of rest wherein the perforation 48 has passed beyond the finger 43 and the perforations 44 and 46 have moved into registry with the fingers 40 and 42, respectively, whereupon the manual switch 57 may be permitted to return to its normal position shown in Fig. 1. When perforations 44 and 46 register with fingers 40 and 42, respectively, the chime C and the light 1 are operated as above described. When perforation 45 later registers with finger 41 the gong G is rung as above described. Subsequently when perforation 47 registers with finger 42 relay 9 receives another impulse of current which extinguishes light 1 at the time of departure. At the next advanced step of the controller 39 perforation 48 again registers with finger 43 thereby energizing relay 59 through ground, bar 49, relay 59, contact N of switch 55 and thence to battery and ground. The energization of relay 59 closes a switch 58 thereby passing another impulse of current to electromagnet 56 over the circuit from ground

through battery, switch 55, contact N, contact F of switch 57, electromagnet 56 to ground as illustrated in Fig. 2. This impulse through electromagnet 56 advances the notched wheel 60 another step which moves the switch 55 from the contact N to the contact F thereby opening the circuit of motor 53 and stopping the advance of the tape 39. Thus the emergency apparatus comes to rest in a position ready to be used again in connection with any of the route indicators R, R', etc., when a corresponding switch 50, 51, etc., is moved to the dotted-line position and the manual switch 57 is again depressed for a brief interval.

From the foregoing it will be evident that the circuit for starting the emergency controller motor 53 comprises the contact N of the two-way electromagnetic switch 55, the circuit for energizing the electromagnet 56 including the contact N of manual switch 57, that the circuit 55—N—58—F—57—56 comprises a branch circuit for energizing the electromagnet 56 to move its switch to the off contact F, and that the branch circuit 49—43—59—N—58 for said relay includes the contact 49—43 on the controller. It will also be evident that the timing of the signals may be varied as desired to fit particular conditions; that more than one emergency circuit may be associated with each dispatching board; and that any desired number or kind of signals may be employed.

I claim:

1. A dispatching system comprising time indicating means, a plurality of route indicators, route means for operating the route indicators in predetermined sequence, normal means for operating the time indicating means in predetermined time relationship to each operation of the route indicators before the expiration of the route indication, emergency means for operating any one of said route indicators out of said predetermined sequence and concomitantly operating said time indicating means, and a manual controller for rendering any route means ineffective when the emergency means is operatively associated with the corresponding route indicator, said time indicating means being responsive both to said normal means and also to said emergency means while the latter is operatively associated with a route indicator.

2. A dispatching system comprising time indicating means, a plurality of route indicators, route means for continually operating the route indicators in predetermined sequence, normal means for operating the time indicating means in predetermined time relationship to each operation of the route indicators before the expiration of the route indication, normally inoperative emergency means for operating said time indicating means and any one of said route indicators

out of said predetermined sequence, and a manual controller for rendering any route means ineffective when the emergency means is operatively associated with the corresponding route indicator, said time indicating means being responsive both to said normal means and also to said emergency means while the latter is operatively associated with a route indicator.

3. A dispatching system comprising time indicating means, a plurality of route indicators, route means for operating the route indicators in predetermined sequence, normal means for operating the time indicating means in predetermined time relationship to each operation of the route indicators before the expiration of the route indication emergency means for operating any one of said route indicators out of said predetermined sequence and concomitantly operating said time indicating means and a manual controller for rendering any route means ineffective when the emergency means is operatively associated with the corresponding route indicator, said emergency means including mechanism for automatically rendering the means ineffective after a single cycle of indications, said time indicating means being responsive both to said normal means and also to said emergency means while the latter is operatively associated with a route indicator.

4. A dispatching system comprising a plurality of time indicators, a plurality of route indicators, normal means for operating the route indicators in predetermined sequence and the time indicators in predetermined time relationship to each other and to each operation of each route indicator before the expiration of the route indication, emergency means for operating any one of said route indicators out of said predetermined sequence and said time indicators in said predetermined time relationship, and a switch associated with each route indicator for shifting its control to said emergency means, said time indicators being responsive both to said normal means and also to said emergency means while the latter is operatively associated with a route indicator.

5. A dispatching system comprising a plurality of time indicators, a plurality of route indicators, normal means for operating the route indicators in predetermined sequence and the time indicators in predetermined time relationship to each other and to each operation of each route indicator before the expiration of the route indication, emergency means for operating any one of said route indicators out of said predetermined sequence and said time indicators in said predetermined time relationship, and a switch associated with each route indicator for shifting its control to said emergency means, said emergency means including mechanism for auto-

matically rendering the first operating means ineffective after operating each time indicator and one route indicator, said time indicators being responsive both to said normal means and also to said emergency means while the latter is operatively associated with a route indicator.

6. A dispatching system comprising time indicating means, a plurality of route indicators, route means for continually operating the route indicators in predetermined sequence, normal means for operating the time indicating means in predetermined time relationship to each operation of the route indicators before the expiration of the route indication, normally inoperative emergency means for operating said time indicating means and any one of said route indicators out of said predetermined sequence, and a manual controller for rendering any route means ineffective when the emergency means is operatively associated with the corresponding route indicator, said emergency means including a manual starter and mechanism for automatically stopping the emergency means after a predetermined time, said time indicating means being responsive both to said normal means and also to said emergency means while the latter is operatively associated with a route indicator.

7. A dispatching system comprising a plurality of circuits, control means separately connected with each of said circuits for closing said circuits in predetermined sequence, a starter for starting said means and mechanism controlled by said means for rendering the means ineffective after each of said circuits has been closed until said starter is again actuated.

8. An electrical system for dispatching purposes and the like, comprising a plurality of circuits, a cyclic controller separately connected to each of said circuits for operating the circuits in sequence during each cycle, means for manually starting the controller to start a cycle of operations, and means responsive to the controller for stopping the controller at the end of the cycle.

9. An electrical system for dispatching purposes and the like, comprising a plurality of circuits, a cyclic controller separately connected to each of said circuits for operating the circuits in sequence during each cycle, a motor for actuating said controller, a circuit for starting said motor, an electromagnetic switch for opening said circuit, and a control circuit for the electromagnet controlled by said controller to stop said motor.

10. An electrical system for dispatching purposes and the like, comprising a plurality of circuits, a cyclic controller separately connected to each of said circuits for operating the circuits in sequence during each cycle, the controller having a rest position at the end of the cycle in which one of said circuits is closed,

a motor for driving the controller, and an electromagnet in said last circuit for stopping the motor when the controller reaches said rest position.

- 5 11. An electrical system for dispatching purposes or the like comprising a signal controller, a motor for driving the controller, means including a two-way switch for starting the motor, an electromagnet for actuating
10 said switch, a two-way manual switch, each of said switches having an on contact and an off contact, a relay switch, a circuit for starting said motor including the on contact of said electromagnet, a circuit for energizing
15 said electromagnet to move its switch to on position including the on contact of said manual switch, a branch circuit for energizing said electromagnet to move its switch to the off contact including the on contact
20 of said electromagnetic switch, said relay switch and the off contact of said manual switch, and a branch circuit for said relay including a contact on said controller and the on contact of said electromagnetic switch.
